WALLPAPER HANGING APPARATUS

Ted R. Wynn, Helena, Ala.

Application April 23, 1951, Serial No. 222,429

3 Claims. (Cl. 216—6)

1

This invention relates to a paper hanging device and more particularly to a device which will automatically apply an even coat of paste to wall paper and apply the paper to the wall or ceiling in a smooth and even manner.

A more specific object of my invention is to provide a paper hanging device embodying a paste container so constructed that the glue is retained therein until removed therefrom by moving the paper across a discharge opening in the container.

A further object of my invention is to provide a device of the character designated including means for determining the correct length of paper required to reach a point which cannot be reached by the device and means for cutting and applying the paper to the wall without further trimming.

A still further object of my invention is to provide a device of the character designated including improved means for correct alignment of the paper before it is applied to the wall.

A device embodying features of my invention is illustrated in the accompanying drawings, forming a part of this application, in which:

Fig. 1 is a sectional view of the device taken along the line I—I of Fig. 2;

Fig. 2 is a front elevational view thereof;

Fig. 3 is a side elevational view thereof;

Fig. 4 is a plan view thereof;

Fig. 5 is a perspective view with certain parts broken away;

Fig. 6 is an enlarged detail view of the discharge opening in the paste container with a roll of paper in position for applying paste thereto;

Fig. 7 is an enlarged side elevational view of the device; and,

Fig. 8 is a sectional view taken along the line VIII—VIII of Fig. 7.

Referring now to the drawings for a better understanding of my invention, the device comprises a frame 10 including spaced side walls 11 and 12 connected together by rods 13. Detachably supported between the side walls 11 and 12 on pins 16 is a paste container 14 which is the shape of an isosceles right triangle as viewed in end elevation. The pins 16 are positioned at each end of the container and on opposite sides thereof so that the container 14 is supported with one side 17 of the right angle lying in a vertical plane as viewed in Fig. 1. The other side 18 of the right angle lies in a plane normal to and is substantially equal in length to the side 17. The diagonal side 19 or hypotenuse of

2

the right triangle joins the side 18 thus forming a sealed upper portion for the container as viewed in Fig. 1. To detachably hold the container in the device one of the pins 16 is provided with threads and a knob 16' for screwing the pin inwardly to engage the container.

While the side 19 of the container forms with each of the sides 17 and 18 an included angle of approximately 45°, the sides 17 and 19 do not join each other but are cut away so as to provide an elongated opening 21 which extends from end to end of the container 14. Secured to the lower ends of the sides 17 and 19 by means of brackets 22 and 23 respectively are felt strips 24 employed for a purpose to be described hereinafter.

The sides 11 and 12 are provided with elongated openings 26 which are positioned immediately below the paste container 14 and extend 20 in a direction substantially parallel to the vertical wall 17 of the container. Rotatably mounted in the elongated openings 26 is a rod or shaft 27 for supporting a roll of wall paper 28.

Mounted on each of the side walls 11 and 12 25 by means of a screw 29 is a spring 31 having extending ends 32 and 33. The lower end 32 of the spring is bent as at 34, so as to lie in a plane substantially normal to the walls of the elongated openings 26 and tends to bias the roll of wall 30 paper 28 toward the felt strips 24 and the opening 21.

The upper ends 33 of the springs 31 are bent so as to lie substantially normal to the side walls 11 and 12 as shown in Fig. 8 of the drawings and 35 fits in an elongated opening 36 of a size to slidably receive the end of the spring. In normal operating position, the end 33 of the spring extends inwardly of the side walls 11 and 12. Mounted for rotation between the ends 33 of the 40 springs is a roller 37 provided with a plurality of annular grooves 38. The ends of the roller 37 are provided with depressions 39 for receiving the inwardly extending ends 33 of the springs. To remove the roller 37 from the device the ends 33 of the springs are pressed outwardly. Rotatably mounted adjacent the roller 37 and in openings 41 in the side walls 11 and 12 is a cutter 42. Adjustably mounted upon the shaft 42 by means of set screws 43 are circular cutters 44 or knives 44. The annular grooves 38 in the rollers 37 cooperate with the circular cutters 44 to trim the edges of the wall paper as it passes 45 between the roller 37 and the shaft 42.

Extending between the side walls 11 and 12 is 50 a bar 46 having mounted thereon a knife 47 for

cutting the wall paper transversely of the length thereof. The knife 47 rides in a groove 48 on the bar 46 and is pulled across the paper by means of a cord 49 in a manner well understood in the art.

Positioned adjacent an upper corner of the device on the side thereof opposite the roll of wall paper 28 and mounted for rotation between the side walls 11 and 12 above the roller 37 is a presser roller 51. The outer surface of the roller 51 extends outwardly of the sides 11 and 12 and engages the outer surface of the wall paper. This construction permits the paper 28 to be applied to the wall from the roller 51 without the sides 11 and 12 coming in contact with the wall.

To permit the removal of short lengths of wall paper from the device, a turn knob 52 is secured to one end of the roller 51. The springs 31 tend to bias the roller 37 toward the roller 51, thus permitting any desired length of paper to be removed from the device by turning the turn knob 52.

Mounted adjacent the upper portion of the side wall 12 is a gauge 53 for determining the point at which the paper must be cut to provide the correct length of paper to reach the ceiling or the like of a room, thus permitting the paper to be cut while in the apparatus and prior to applying it to the uppermost portion of a wall 54. The gauge 53 comprises an elongated bar 56 having a longitudinally extending slot 57 adjacent the lower portion thereof. The bar 56 is adjustably mounted to the side wall 12 by means of a screw 58 which may be employed to clamp the bar in any set position. Secured to the upper edge of the wall 12 on opposite sides of the bar 56 are guide members 59 and 61 which limit the movement of the bar 56 to a direction normal to the upper edge of the wall 12.

Secured to two of the rods 13 at the side of the device opposite the roll 51 is a curved handle 62. The lower end of the handle contacts the wall 54 when paper is being applied thereto and prevents the side walls 11 and 12 from coming in contact with the wall. The handle 62 is provided with a laterally extending opening 63 adjacent the wall engaging end thereof. Slidably fitting in the opening 63 is a bar 64 which is adjustably secured to the bar 62 by means of a set screw 66. The bar 64 extends laterally in a direction parallel to the axis of the roller 51 and is clamped in position so that the end thereof contacts the edge of the paper 28 when the paper is correctly aligned or when the edge of the paper is normal to the bar 64.

If desired, the paper may be passed over the roller 37 and thence under the presser roller 51 in a counter-clockwise direction as viewed in Fig. 7. The paper is then applied to the wall by moving the device from the top of the wall toward the bottom thereof, thus permitting gravity to aid in moving the device over the wall. To apply paper in this manner, the circular cutters 44 and the knife 47 would be placed on the opposite side of roller 37 from that shown in the drawings. Also, the gauge 53 would be mounted adjacent the bottom of the device so as to project downward therefrom.

From the foregoing description, the operation of my improved paper hanging device will be readily understood. The paste container 14 is removed from the device and filled with paste through the opening 21. The container 14 is then inserted between the walls 11 and 12 and between the pins 16, and the pin having the knob

16' is screwed inwardly as clearly shown in Fig. 1. In this position the paste does not flow from the container but remains therein until removed therefrom by bringing the wall paper 28 in actual contact with the paste at the bottom of the container. While I do not know just what prevents the paste from flowing from the container 14 as constructed, it is believed that by providing a sloping wall forming an included angle with respect to a vertical wall of approximately 45°, vertical support is provided for the thick paste. Also, the thick paste prevents easy flow of air upwardly therethrough thus providing a partial vacuum at the top of the container. I have found in actual practice that the partial vacuum created will not prevent the paste from flowing from the container unless the container is constructed as described above.

The springs 31 keep the surface of the paper 28 in contact with the felt strips 24 thus assuring that an even coat is applied to the paper. The paper 28 next passes over the roller 37 where the edges are trimmed by the circular cutters 44. From the roller 37 the paper passes over the bar 46 and the roller 51 where it is applied to the wall 54.

To apply the paper to the wall, the operator sets the gauge 53 to compensate for the width of the molding 60 and aligns the bar 64 with the edge of the paper. The roller 51 is then pressed against the wall as the device is moved upwardly. When the top of the gauge 53 contacts the ceiling the cord 49 is pulled thus cutting the paper the correct length to reach the molding. The gauge 53 is lowered by loosening the screw 58 and the device is then moved upwardly to the ceiling. As the roller 51 applies the paper to the wall, it presses out all the wrinkles and leaves a smooth surface.

In applying wall paper, it is often necessary to have short pieces of paper for papering spaces which cannot be reached by the paper hanging device. To provide such short pieces of paper, the knob 52 is turned until the desired amount is released. The short piece of paper is then ready to be applied to the wall.

From the foregoing it will be apparent that I have devised an improved paper hanging device which will apply the paper to the wall in a smooth and even manner. By providing a paste container which will retain the paste therein until removed by the paper there is no waste of paste and the entire surface of the paper is coated.

While I have particularly described my improved apparatus as being useful for applying paper to walls, in practice I find that due to its light construction it can be used effectively to apply paper to ceilings also.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. A paper hanging device comprising substantially rectangular side walls spaced laterally from each other, a paste container mounted between said side walls having walls in the shape of an isosceles right triangle as viewed in end elevation, said container being mounted with one leg of the right triangle lying in a plane substantially normal to the bottom edge of said side

walls, there being an opening in the bottom corner of said container extending from end to end thereof, there being elongated vertically extending openings in said side walls adjacent the bottom of the paste container, means to rotatably mount a roll of wall paper between said side walls and in said elongated openings, leaf springs having extending ends secured intermediate the ends thereof to said side walls, one of said spring ends biasing the roll of wall paper upwardly in said elongated opening toward the opening in the bottom of the paste container, the other of said spring ends being bent inwardly toward each other, there being a second elongated vertically extending openings in the side walls for receiving said inwardly bent ends of the springs, a roller detachably mounted for rotation between said inwardly bent ends of the springs and having a plurality of annular grooves therein, circular cutters cooperating with said grooves for trimming the edges of the paper, a presser roller rotatably mounted between the side walls above said roller having annular grooves therein and frictionally engaging the same, and means adjacent the presser roller for severing the paper transversely of the length thereof.

2. A paper hanging device as defined in claim 1 in which a turn knob is secured to one end of the presser roller for releasing short pieces of wall paper with paste applied thereto.

3. In a paper hanging device, a frame embodying laterally spaced side walls, a paste container triangular in transverse section extending between the said side walls and detachably

mounted thereon, there being an opening in the lowermost corner of said container extending the length thereof, means for rotatably supporting a roll of paper adjacent and below said opening, 5 a roller rotatably mounted between said side walls with a portion of its periphery projecting outwardly of said side walls over which the paper passes after it has passed said opening in the paste container, a handle secured to said side walls and having a lower end of a length to contact the wall to be papered and hold said side walls of the device out of contact with the wall to be papered, and a bar adjustably secured to the lower end of the handle and extending laterally therefrom in a direction substantially parallel to the axis of the roller for aligning the device by reference to an edge of the paper being applied.
